UNITED STATES PATENT OFFICE.

LOUIS T. FREDERICK, OF VALPARAISO, INDIANA, ASSIGNOR TO CHICAGO MICA COMPANY, OF VALPARAISO, INDIANA, A CORPORATION OF ILLINOIS.

METHOD OF MAKING MICA PLATE.

Application filed December 23, 1926. Serial No. 158,629.

My invention relates to the making of mica plate which is a known article consisting of mica flakes arranged in over-lapping relation and held together by shellac or other suitable binder. In order to consolidate this composite material it is necessary to subject it to pressure usually accompanied by heat, and difficulty is frequently experienced in preventing the platens of the press from sticking to the composite and loosening or stripping off some of the outer flakes, thus reducing the quality of the product. The purpose of my invention is to provide a method for obviating this difficulty.

15 The method is illustrated by the accompanying drawings in which—

Figure 1 is an exploded view of a piece of mica plate with two sheets on each side designed to intervene between the product 20 and the platens of the press in which it is to be consolidated.

Figure 2 is a vertical sectional view showing the platens and associated parts of a press with the mica plate and backing sheets in position.

Figure 3 is a perspective view of the compressed whole showing the outer stiffer backing sheets in process of removal.

Figure 4 is a perspective view showing the 30 method of stripping off the inner highly flexible backing sheet from the product.

Like numerals denote like parts throughout the several views.

In practicing this method I first assemble 35 the mica flakes and binder to produce a "plate" 10. It will be understood that the ordinary binders such as shellac are more or less sticky, especially when hot, and it has always been a problem to prevent the work from sticking to the pressing element after the pressing operation was completed. Great care has been necessary to prevent the pressing elements from loosening or actually pulling away from the work portions or all of a 40 greater or less number of flakes. This of course produces an inferior grade of product. According to my invention I avoid this by taking the plate 10 in its unpressed form as shown in Figure 1, and place against 45 the faces thereof a highly flexible sheet 12 of fabric. I have found that a highly desirable fabric for the purpose is cheese cloth. It is light in weight, comparatively inexpensive and highly flexible. On the outer surface of the cheese cloth I place backing sheets

14 of much heavier and much less flexible material. I have found that a very suitable material for the purpose is heavy cotton duck or canvas. After the parts are assembled in this manner they are introduced into a press. 50 Presses for the purpose are well known and exist in different forms. In Figure 2 I have shown a cross section of a portion of a suitable type of press. This is provided with upper and lower platens 16, 18 respectively which are hollow in order that they may 55 permit the circulation of a heating medium, such as steam, within them. These platens may be operated by any suitable mechanism, for example, the mechanism illustrated more 60 or less diagrammatically in Figure 2 and including plunger stems 22, 24. These heated platens when forced toward each other in accordance with usual practice consolidate and flatten the mica plate to produce a hard 65 and strong finished product. After the pressing operation has been completed the pressure is released and the work with its backing sheets is removed from the press.

The next operation is to remove the back- 70 ing sheets, which may be accomplished easily by simply taking hold of one corner and bending it back and leaving it off in the manner suggested in Figure 3. As these outer back- 75 ing sheets or pads are stiff compared to cheese cloth they do not flex sharply but leave the inner backing sheet more or less at right angles to the surface. In other words, the portion momentarily leaving the inner sheet rises more or less perpendicularly and if in direct 80 contact with the mica flakes would have a strong tendency to loosen some of the outer flakes, but by employing intervening sheets 85 12 no harm is done to the product because the flakes are held by the inner sheets. 90

The next step is to remove the inner sheets. 95 The operator first loosens the corner of one of them and then draws it back at a sharp angle, as shown in Figure 4. In other words, he strips off the inner sheet 12 by exerting 100 tension obliquely backward in a direction which is at a comparatively sharp angle with the plane of the article. The result is that as the sheet is highly flexible there is no appreciable radius of curvature at the point where the sheet is leaving the work, and hence the pull on the mica flakes instead of being more or less perpendicular to the surface of the plate is more nearly along the surface of the plate. The flakes, of course, are much 110

more able to resist a pull in their own plane than in a direction perpendicular thereto, and the result is that they remain tightly in place. It will be understood that in the better grade of mica plate the proportion of binder is kept as low as possible. The mica itself has much higher dielectric properties than shellac and similar binders, and hence it is desirable to keep the proportion of binder as low as possible, for illustration 2, 3 or 4% by weight of the finished product. With this low percentage of binder my method is of special advantage in reducing as it does, almost to nothing, the tendency to pull the outer flakes away from the rest of the plate. The process adds practically nothing to the cost of manufacture because cheese cloth and similar material is cheap in itself and in most cases may be used over and over again.

Having thus described my invention, what I claim as new and desire to secure by Letters Patent is:

1. The method of making mica plate which consists in assembling mica flakes in overlapping relation in association with a binder, placing the same between two heated plates which are adapted to be pressed together, placing a thin loosely woven and highly flexible, non-metallic sheet of fabric between each plate and the mica flakes, subjecting the whole to pressure and finally stripping off the said woven sheet by tension exerted obliquely backward.

2. The method of making mica plate consisting in assembling mica flakes in overlapping relation in association with a binder between upper and lower platens adapted to be pressed together, spreading a loosely woven sheet of highly flexible non-metallic material over each side of the flakes, placing a less flexible pad over the first named sheets, sub-

jecting the whole to pressure, first removing the last named pads and finally stripping off the first named sheets.

3. A method of making sheets of mica flakes and binder by pressing the same between hot platens which consists in placing a loosely woven highly flexible non-metallic sheet of material next to each side of the flakes and inserting a non-metallic and less flexible backing pad between the first named loosely woven sheet and the platen, subjecting the same to pressure, then removing the backing pads and then stripping the loosely woven sheet from the flakes at an oblique angle to the surface of the flakes.

4. The method of making mica plate consisting in assembling mica flakes in overlapping relation in association with the binder, placing the same between sheets of cheese cloth, placing a backing sheet on the surface of the cheese cloth, subjecting the whole to pressure, then removing the backing sheet separately and finally stripping off the cheese cloth by pulling it backward at a sharp oblique angle relatively to the surface of the plate.

5. The method of making mica plate consisting in assembling mica flakes in overlapping relation in association with a binder, placing a cheese cloth against each side of the mica plate in contact with the flakes, and placing a heavy textile fabric backing sheet next to the cheese cloth, subjecting the same to pressure between heated platens, then removing the pressure and stripping off the backing sheets and then stripping off the cheese cloth at an acute angle to the surface of the flakes.

In witness whereof, I have hereunto subscribed my name.

LOUIS T. FREDERICK
